UNITED STATES PATENT OFFICE

119,362

DESIGN FOR A NAPKIN

Charles Kenny, New York, N. Y.

Application January 29, 1940, Serial No. 89,838

Term of patent 3½ years

To all whom it may concern:

Be it known that I, Charles Kenny, a citizen of the United States, residing in New York city, in the county of New York and in the State of New York, have invented a new, original, and ornamental Design for a Napkin, of which the following is a specification, reference being had to the accompanying drawing, forming part thereof.

The single figure is a plan view of a napkin embodying my new design.

I claim:

The ornamental design for a napkin, substantially as shown.

CHARLES KENNY.
